UNITED STATES PATENT OFFICE.

JAMES H. BEAN, OF SISSON, CALIFORNIA.

LATCH.

Application filed April 28, 1924. Serial No. 709,573.

The present invention relates to latches for doors and other closures, particularly those that are hingedly mounted. The object is to provide a simple and very effective latch 5 that will become automatically operative to hold the door in its closed position when moved to such position and yet will permit the same to be opened by sufficient pressure.

In the accompanying drawings:—

10 Figure 1 is a side elevation of the preferred embodiment of the invention,

Figure 2 is a sectional view on the line 2—2 of Figure 1,

15 Figure 3 is a perspective view of the retaining member,

Figure 4 is a view in elevation of a modified form of construction,

Figure 5 is a sectional view on the line 5—5 of Figure 4,

20 Figure 6 is a detail sectional view on the line 6—6 of Figure 5,

Figure 7 is a view in elevation of the retainer shown in Figures 4—6 inclusive.

In the embodiment disclosed in Figures 1, 25 2 and 3, a portion of a door or other closure is shown at 8, and the frame for the same is illustrated at 9. In the margin of the door, and

30 opening through the free edge of the same, is formed a socket 10, and embracing said portion is a keeper 11 preferably comprising a

U-shaped strip of metal, the intermediate transverse portion 12 of which connecting the side legs, extends across the socket 10. This

portion is provided with an opening 13. Located in the outer portion of the socket is a

35 latch member in the form of a rotatable ball 14 of greater diameter than the opening 13 and having its outer portion projecting through the same. A coiled spring 15 is located in the socket 10 and is interposed be-

40 tween the bottom of the same and the ball, being compressed sufficiently to yieldingly

urge the ball outwardly through the opening, as will be clear by reference to Figure 2.

45 A coacting retaining member is mounted on the frame 9 and preferably consists of a single strip of yielding metal, having its

terminal portions 16 and 17 arranged in right angular relation and connected by an out-

50 standing intermediate bowed portion 18 con-

stituting a projecting striker element. The

portion 16 is arranged flat against one side

of the frame 9 and is provided with a plu-

rality of openings through which suitable fasteners 19 may be passed. The portion 17 55 extends alongside the inner edge of the frame in spaced relation thereto and has an opening 20 constituting a socket that receives the projecting portion of the latch ball 14.

When a door and the frame has mounted 60 thereon the coacting members, it will be evident that if the door is swung to closed position the projecting portion of the ball latch 14 will strike against the loop 18 and be forced rearwardly thereby, the arm 17 65 yielding also to the movement of the ball thereover until said ball enters the socket 20, whereupon the door will be stopped and upon sufficient opening pressure against the door the ball will ride out of the socket and permit 70 the free opening of the door.

The structure shown in Figures 4—7 inclusive, is very similar to the above described, except that a flat sided roller is substituted 75 for a sphere. This roller is designated 14^a and may be mounted in a metallic casing 14^b placed in the outer portion of the socket. The keeper is designated 11^a and the coiled spring acting against the roller 14^a is illustrated at 15^a. The retaining member consists of 80 angular terminal portions 16^a and 17^a connected by an integral loop 18^a, forming the striker. Obviously this structure operates in the same manner as that above described.

From the foregoing, it is thought that the 85 construction, operation and many advantages of the herein described invention will be apparent to those skilled in the art, without further description, and it will be understood that various changes in the size, shape, proportion and minor details of construction may be resorted to without departing from the spirit or sacrificing any of the advantages 90 of the invention.

What I claim is:—

The combination with a frame member and a closure member having adjacent edges, of a substantially U-shaped keeper embracing the said edge of one member and having an opening through its central portion, a rotatable latch member behind the keeper and of greater area than the opening, said latch member projecting through the opening, a spring bearing against the rear side of the latch member to yieldingly hold it in projecting position through the opening, and a 105

second keeper member secured to one side of the other member and having a free yielding portion extending across the edge of the said member to which it is secured and between the two members in line with the first keeper member, said yielding portion having an opening therethrough of less area than the opening in the first keeper member and

snugly receiving the projecting end of the rotatable latch member, said spring being ¹⁰ capable of movement toward and from the first keeper member to insure said snug reception.

In testimony whereof, I affix my signature.

JAMES H. BEAN.
